[57] CLAIM

The ornamental design for a textile fabric, as shown and described.

DESCRIPTION

FIG. 1 is a top plan view of a textile fabric showing a first form of my new design wherein the background is light; and,

FIG. 2 is a top plan view of a textile fabric showing another form of my new design wherein the background is dark.

The dotted lines outline a design unit which is repeated over the fabric in regular succession as indicated by the extensions beyond the unit boundaries.
